(57) **CLAIM**

We claim the ornamental design for a bottle, as shown and described.

DESCRIPTION

FIG. 1 is a front perspective view of a bottle showing our new design;

FIG. 2 is a rear perspective view of the bottle design shown in FIG. 1;

FIG. 3 is a front view of the bottle design shown in FIG. 1; FIG. 4 is a rear view of the bottle design shown in FIG. 1; FIG. 5 is a right view of the bottle design shown in FIG. 1; FIG. 6 is a left view of the bottle design shown in FIG. 1; and,

FIG. 8 is a bottom view of the bottle design shown in FIG. 1.

The broken lines in the drawings showing the bottle illustrate the portions of the bottle that form no part of the claimed design.
